UNITED STATES PATENT OFFICE.

JOHN W. IPPERS, OF NEW YORK, N. Y., ASSIGNOR TO ALBERT HENRY
WALKER, OF NEW YORK, N. Y.

PHOTOMECHANICAL PRINTING.

No. 843,947.

Specification of Letters Patent.

Patented Feb. 12, 1907.

Application filed November 26, 1906. Serial No. 345,012.

To all whom it may concern:

Be it known that I, JOHN W. IPPERS, a citizen of the United States, and a resident of the city of New York and the State of New York, have invented a new and useful Improvement in Photomechanical Printing, of which the following description and claims constitute the specification.

The object of my invention is to photomechanically make depressed printing-surfaces with non-intersecting parallel ridges on the peripheries of metal rollers, the function of the depressed printing-surfaces being to carry "color" for deposit on continuous strips of cloth or paper and the function of the parallel ridges being to prevent the ductor, which removes the color from the non-printing surfaces of the roller, from descending to the bottoms of the depressed printing-surfaces and removing a considerable part of the color therefrom.

The relations of my invention to the prior art of photomechanical roller-printing can be learned by comparing this specification with Letters Patent of the United States No. 812,495, granted on my invention February 13, 1906, and Letters Patent of the United States No. 788,377, granted on the invention of Henry L. Reckard April 25, 1905. A copper roller having a depressed printing-surface in the form of a star is indicated by Figure 3 of the drawings of my Patent No. 812,495; but that printing-surface is so small in area that it does not require any parallel ridges or other projections rising upward from its bottom to prevent the ductor from descending into that depression and removing any considerable amount of color therefrom. The specification of that patent does not, therefore, attend to that subject; but the Reckard patent, No. 788,377, does attend to that subject by means of a particular method fully set forth in the specification of that patent and constituting an essential part of each of the first six claims thereof. Fig. 9 of that Reckard patent may be taken to represent the periphery of a metal roller provided with a depressed printing-surface having the shape of a reversed letter R and having diagonal parallel ridges rising upward from the bottom of that depressed printing area and intersecting with the black non-printing area of the periphery of that roller. Close inspection of Fig. 9 of that Reckard patent will show that the black

diagonal lines on the reversed letter R intersect at their ends with the plain black areas of the figure, and careful study of the specification of the Reckard patent will show that such intersections must always result from the Reckard method of making those black diagonal lines and that the parallel diagonal ridges of metal which ultimately result in the depressed printing-surfaces of a metal roller made by the Reckard process must intersect with the non-printing surfaces of that roller.

The Reckard method of making parallel ridges in the bottoms of depressed printing-surfaces of metal rollers, while available and useful for that purpose, is not perfect, because perfection requires that the parallel ridges in the bottoms of depressed printing-surfaces of metal rollers shall stop slightly short of intersecting at their ends with the non-printing surfaces of such rollers, as the diagonal parallel lines of Fig. 10 of the drawings which accompany this specification are shown as stopping short of intersecting with the black background of that figure.

The desirability of leaving a narrow and uniformly-depressed border at the edge of a depressed printing-surface of a metal printing-roller arises from the desirability of applying color with smooth continuity at the edge of every such deposit and from the fact that where the parallel ridges quite reach and intersect with the non-printing surfaces of an intaglio metal printing-roller the resulting edges of the deposit of color are not quite sharply and evenly defined. Where the metal parallel ridges are located on the depressed printing-surfaces of a metal roller, as the black parallel lines of Fig. 10 of my present drawings are shown to be located upon the white parallelogram of that figure the color which is left upon the periphery of the roller after the ductor has done its work thereon is deposited in the grooves which are represented by the white lines of that figure. When that color is transferred from such a metal roller to a strip of cloth, that application is in the form of corresponding lines; but capillary attraction immediately operates to blend together all the color deposited on the cloth from the diagonal grooves, so as to result in a continuous application of color to the cloth over that part of its surface which was opposite to the depressed surface

of the roller when the cloth passed over the roller in the printing-machine. Capillary attraction will also cause the color to spread slightly outward from the lines which receive 5 deposits of color from the outer continuous grooves of the depressed printing-surface; but inasmuch as those outer grooves are uniform the outward spreading of the color will also be uniform, whereas if the parallel copper ridges 10 extended quite to the non-printing surfaces of the roller, while capillary attraction would operate to cover the cloth opposite to the depressed printing-surface of the roller, the outer edges of that deposit would appear to 15 be slightly rough and irregular instead of being even and continuous, as they will be if a continuous depression is made all around the edges of the depressed printing-surface. The reason why extensions of the parallel copper 20 ridges quite to the non-printing surfaces of the roller would cause the outer edges of the deposit of color on the cloth to be slightly rough and irregular resides in the fact that the separate capillary deposits of color within 25 the cloth between the unconnected ends of the parallel grooves would not be quite equal in copiousness to the separate direct deposits of color upon the cloth from the ends of the parallel grooves themselves.

30 The nature of my present invention consists in what I believe to be the first photomechanical method of so making parallel ridges in the bottoms of depressed printing-surfaces of metal rollers that the ends of 35 those ridges will not intersect with the non-printing surfaces of the rollers; and I will now proceed to describe that method in detail with the assistance of the accompanying ten figures of drawings.

40 Fig. 1 represents a translucent glass sheet having thereon a design consisting of a flat area of opaque surface in the form of a rectangle. Fig. 2 is a view of a lithographic stone which has photographically received 45 an acid-resisting film upon the surface, which is represented in the figure by a hollow black rectangle and the naked surface of which stone has been thereupon etched down to a lower level to constitute the depressed surface, which is indicated by numeral 2. Fig. 50 3 is a central vertical cross-section of the stone of Fig. 2. Fig. 4 is a view of a translucent glass sheet which has been provided with parallel black lines separated by parallel transparent lines of the same width upon 55 one of its sides. The black lines upon the sheet of Fig. 4 are permanent and may be produced in any of the ways in which permanent black lines are made across glass 60 plates to be used as screens of light in the art of photomechanical printing. Fig. 5 is a view of another lithographic stone, which has been provided photographically through the translucent screen of Fig. 4, with narrow 65 parallel printing-surfaces represented by the

black parallel diagonal lines of that figure and separated by narrow non-printing surfaces represented by the white diagonal lines of that figure. Fig. 6 is a view of a sheet of lithographic transfer-paper, which has 70 received deposits of lithographic transfer-ink on its black diagonal lines, from the black diagonal printing-lines upon the stone of Fig. 5. Fig. 7 is a vertical cross-section of the stone of Figs. 2 and 3, with the sheet of transfer-paper 6 pressed down upon the upper surface of the stone, including its black border and its depressed area 2 within that border. Fig. 8 is a view of the stone of Figs. 2, 3, and 7 after the sheet of transfer-paper 6 75 has been removed therefrom. Fig. 9 is a vertical cross-section of the stone of Fig. 8 with a sheet of elastic white cardboard 10 pressed down thereon so as to receive an impression of ink therefrom. Fig. 10 is a view 80 of that sheet of fine white cardboard after it has received that impression of ink and has been removed from the stone.

The design on the translucent glass sheet of Fig. 1 may be made photographically or 90 mechanically.

The depressed surface 2 on the face of the lithographic stone of Fig. 2 is produced as follows upon a plain polished planographic surface of a lithographic stone: I make a sensitizing solution by beating the whites of three eggs in four and a half ounces of water and by adding thereto three drams of bichromate of ammonia dissolved in four and one-half ounces of water and by adding fifteen 95 drops of liquid ammonia to the whole, and I keep and use this sensitizing solution in a dark room. I then warm the plain lithographic stone by pouring hot water over it, and then I flow the sensitizing solution over 100 it and dry thereon the film thus deposited. Thereupon I clamp the translucent glass plate of Fig. 1 down upon the sensitized stone and in close contact therewith. Then I expose the sensitized stone to light through 105 the translucent glass plate, about one minute if the light be direct sunlight or about eight minutes if it be clear north daylight. I next remove the translucent glass plate from the plain lithographic stone in a dark room and 110 at once roll transfer-ink evenly over the entire sensitized surface of the stone. I then flow cold water over that inked surface and wash away with a cotton ball all the ink 115 which was deposited on that area of the stone which was under the opaque area of the glass plate during the exposure; but that washing does not disturb the ink on those areas of the stone which were under the translucent border of the glass plate at that 120 time. Thereupon I dust powdered rosin over the stone, and it is taken by the inked areas of the stone, but not by the area from 125 which the ink was washed away and which is the white area of Fig. 2. Then I heat the 130

stone to a temperature high enough to melt the powdered rosin into the ink to which it has adhered. This heating results in changing the ink on the surface of the stone into an 5 enamel, and that enamel will protect those areas of the stone which are covered thereby from the action of the etching liquid, which I next apply to the stone. That etching liquid consists of a solution of five ounces of nitric acid of thirty-five-per-cent. strength and 10 one pound of gum-arabic and one pint of warm water dissolved together and filtered. I leave that strong nitric-acid solution on the stone two or three minutes, more or less, until 15 it has reduced the level of the naked area of the stone one-thirtieth of an inch, more or less, below the enameled areas of the stone. Thereupon I wash away the surplus solution with water and then dry the stone till no 20 water remains thereon. I next apply to the stone a solution of one ounce of acetic acid in ten ounces of water, the function of which application is to make the naked area of the stone receptive of greasy ink instead of being 25 repellent thereof, as it would be otherwise as the result of the application of the strong nitric-acid solution thereto.

The ruled glass screen of Fig. 4 having been made or purchased, as the case may be, 30 is a permanent utensil which is usable in any number of instances of the performance of my process. The parallel opaque and transparent lines on that screen should each be about one-eightieth of an inch wide, though 35 they are shown wider than that in Fig. 4.

The lithographic stone of Fig. 5 has a planographic face crossed by parallel ink-receiving and non-ink-receiving lines, which ink-receiving lines are indicated by the black lines 40 and which non-ink-receiving lines are indicated by the white lines of Fig. 5. Those ink-receiving and non-ink-receiving lines are produced in any proper photolithographic manner and by the action of light passing through 45 the ruled screen of Fig. 4 when that ruled screen is clamped down upon the stone of Fig. 5 after that stone has been properly sensitized.

The sheet of transfer-paper of Fig. 6 is not 50 a permanent utensil, and such a sheet requires to be made for each instance of the performance of my process by simply pressing a proper sheet of white transfer-paper down upon the stone of Fig. 5 after that 55 stone has been properly rolled with transfer-ink, so that the sheet of transfer-paper may be provided with heavily and uniformly inked lines corresponding in width with the inked lines on the stone of Fig. 5. The 60 transfer-paper of Fig. 6 being thus freshly inked is pressed immediately down upon the lithographic stone of Figs. 2 and 3, as shown in Fig. 7. Those portions of the inked lines of the transfer-paper 6 which are thus pressed 65 down upon the enameled black border of

the stone of Figs. 2 and 3 simply print black parallel lines across that black border, but do not in so doing effect any appreciable result. Those portions of the inked lines of the transfer-paper 6 which are pressed 70 down upon the naked depressed area 2 of the stone of Figs. 2 and 3 deposit parallel lines of black ink across that area, as shown in Fig. 8, and the black lines thus deposited may or may not intersect with the inner 75 edges of the black enameled border of the stone, because the transfer-paper is flexible and may or may not press quite into the corners 80 of the depressed surface 2. I next apply a weak nitric-acid solution to the enameled 85 and inked stone of Fig. 8, which solution consists of five ounces of nitric acid of thirty-five per cent. strength, with two pounds of gum-arabic and three pints of water dissolved and filtered. I then apply to the 90 stone a solution of two ounces of gum-arabic and six ounces of water in a thin and even film and allow it to dry on the stone; but this application is so thin that it does not adhere to the enameled areas of the 95 stone nor to its inked diagonal lines, but only to the narrow naked spaces between those lines. I then apply to the stone a mixture 100 of equal parts of asphalt-varnish and turpentine, which mixture removes all the ink which was deposited on the stone by the transfer-sheet 6, but does not disturb the enameled border of the stone nor the gum which adheres to the uninked spaces between the inked lines on the depressed area 105 2 of the stone. I then apply water with a sponge to that depressed area, and thus remove that gum, but do not disturb the asphalt. At this stage of the process the inked 110 diagonal lines are covered with asphalt, while the narrow spaces between them are left naked. Thereupon water is applied to the stone, which is absorbed by its naked areas, but is repelled by its enameled areas and by those which are covered with asphalt. Transfer-ink is then applied to the stone and 115 is received by the enameled border and by the areas which are covered with asphalt, but is not received by the narrow naked spaces between those areas. I then dust powdered rosin over the stone, which is 120 taken by the inked diagonal lines, but not by the spaces between those lines. I then change that rosined ink into enamel by the application of heat, and then I etch the 125 spaces between the enameled lines with my strong nitric-acid solution a few seconds. In this condition of the stone the enameled diagonal lines are raised somewhat above the naked spaces between them, and those 130 spaces are repellent of ink, because they were last etched with nitric acid. I then roll the entire stone with lithographic ink, which ink is received by the enameled border of the stone and by the enameled diagonal lines 135

across the depressed surface 2 of the stone. I then press a sheet of white elastic cardboard down upon the stone, as shown in Fig. 9. That cardboard being comparatively stiff 5 does not bend sharply enough to reach into the corners 7 of the depression 2 of the stone, but does bend enough to be pressed down upon the whole floor of that depression, except only a narrow border around the edges 10 thereof. The shape taken by the cardboard when thus pressed down upon the stone is shown in Fig. 9, where it appears that the cardboard does not receive ink from the floor of the depression 2 immediately adjacent to the lower corners 7 of that depression, though it does receive ink from all portions 15 of the floor of that depression except immediately adjacent to those corners. For this reason the cardboard when removed from the stone will have received a continuous printing of ink from the black enameled border of the stone and will have received printings of ink from the black enameled lines on the floor of the depressed area 2 of the stone; but the ends of those black lines of ink-printing stop short of intersection with the printed border of the cardboard to about the extent which they are shown as doing in Fig. 10.

The printed cardboard sheet of Fig. 10 is 30 the net product of all the transactions thus far described in this specification. That figure is presented as representative of any simple or complex design, which when multiplied or not multiplied may constitute a pattern exactly large enough to cover the periphery of a metal printing-roller. For example, such a design may cover a parallelogram six inches by five and a quarter inches in dimensions, and the surface of that parallelogram may be composed of any number of regular or irregular white areas provided with parallel black lines and surrounded by flat black spaces with which those black lines stop short of intersecting.

45 Having produced by the program above set forth a sheet of cardboard having dimensions six inches by five and a quarter inches and having a more or less complicated and multifarious design represented thereon by 50 white areas occupied by non-intersecting black lines, like the white area of Fig. 10, I can produce seventeen duplicates of that sheet by printing on seventeen sheets of white cardboard from the same lithographic 55 stone as that from which the first one was printed. I can then fasten the eighteen duplicate sheets thus produced upon a flat wooden board or zinc sheet without any spaces between them, so that they will exactly 60 cover a parallelogram having a surface of thirty-six inches by fifteen and three-quarter inches, and which surface may be identical in dimensions with the periphery of a metal roller thirty-six inches long and 65 about five and one-quarter inches in diam-

eter. The eighteen sheets of cardboard being thus combined together upon a flat board may be made to compose a harmonious pattern combined of eighteen repetitions of one original design, and every space occupied by 70 non-intersecting diagonal lines, which appears upon the whole pattern, may ultimately result in a continuous deposit of "color" made on a strip of cloth from a metal roller and the entire pattern may be 75 printed on that strip, once for each revolution of the roller in a printing-machine.

My present invention stops with the production of one sheet of cardboard, such as that typically represented by Fig. 10, for the 80 above-suggested multiplication of that design does not involve invention and because the proper process for proceeding forward from the design thus multiplied to printing the complete pattern upon a continuous 85 strip of cloth is described in my Letters Patent No. 812,495, of February 13, 1906. In that patent, Fig. 1 may be taken as representative of a translucent photographic negative having dimensions thirty-six inches by 90 fifteen and three-quarter inches and made in a large photographic camera from the combined cardboard pattern which is above set forth. Such a photographic negative being made with many uniformly-translucent 95 areas and many uniformly-opaque areas, that negative may be used to photographically print upon a flat gelatin plate of corresponding dimensions, and that flat gelatin plate may be then developed and dried and supplied with transfer-ink and used to transfer that ink to the periphery of a metal roller, and that metal roller, being etched and otherwise treated, as set forth in that patent, 100 may be used in a printing-machine to apply 105 color to a continuous strip of cloth. In that use the parallel ridges in the bottoms of the depressed printing-surfaces of the roller operate to prevent the ductor from scraping the color out of those depressions, and the non-intersection of the ends of the ridges with the non-printing surfaces of the roller results in a highly desirable sharpness of edge in the printing done on the cloth from those depressed printing-surfaces, while capillary attraction 110 results in blending into a continuous 115 deposit all the color which reaches the cloth from the grooves between the ridges.

A lithographic stone is said in the foregoing 120 description to be the material of the block of Figs. 2, 3, 7, 8, and 9; but a metal plate may be employed instead of a lithographic stone to perform the function of that block in substantially the same way in which that function is performed by a lithographic stone 125 having a depressed surface like that indicated by the numeral 2, and the method of sensitizing the surface of a metal plate to fit it for exposure through a sheet which is partly transparent and partly opaque and 130

the method of developing that exposed surface and the method of etching down some portion or portions of that developed surface into depression and the method of preparing the surfaces of an etched metal plate to properly print from its different levels upon cardboard will differ in particulars, which will be apparent to photomechanical engravers, from those corresponding methods which have herein been described as applicable to a lithographic stone for those purposes. So, also, a lithographic stone or metal plate may mechanically receive an acid-resisting film or deposit on some portion or portions of its surface instead of receiving such a film or deposit photographically, and thereupon the other portion or portions of its surface may be etched down to a lower level for the purposes described in this specification. Moreover, a lithographic stone or metal plate having been provided with a depressed surface like that indicated by the numeral 2 may have that depressed surface provided with parallel printing-lines by some other process than that described in this specification for that purpose. My invention is not limited to the particular methods or to the particular materials which it describes; but it is limited to the processes which are defined in the following claims.

I claim as my invention—

1. Making a photographically-sensitive surface on a lithographic stone or metal plate: exposing that sensitive surface to light through a sheet which is partly transparent and partly opaque: developing that exposed surface into a condition in which whatever area of the stone or plate was under a transparent area of the sheet during the exposure, will resist etching liquid, while whatever area of the stone or plate was then under an opaque area of the sheet, will not resist etching liquid: etching down into a depressed

area, whatever area of the stone or plate is thus made subject to etching: putting the stone or plate into a condition in which it will receive ink over any undepressed area, and will receive ink on parallel lines on the floor of any depressed area thereof, but will not receive ink on the parallel spaces between those parallel lines: applying ink to those surfaces and lines of the stone or plate which will receive ink: printing a continuous area from any undepressed surface of the stone or plate upon a sheet of cardboard, while printing parallel lines upon the same sheet from whatever area of the stone or plate is depressed, but which parallel lines stop short of intersecting with any continuous printed area on the cardboard.

2. Preparing a surface on a lithographic stone or metal plate, so that some of its areas will resist etching liquid, while other of its areas will not resist etching liquid: etching down into a depressed area, whatever area of the stone or plate is thus made subject to etching: putting the stone or plate into a condition in which it will receive ink over any undepressed area, and will receive ink on parallel lines on the floor of any depressed area thereof, but will not receive ink on the parallel spaces between those parallel lines: applying ink to those surfaces and lines of the stone or plate which will receive ink: printing a continuous area from any undepressed surface of the stone or plate upon a sheet of cardboard, while printing parallel lines upon the same sheet from whatever area of the stone or plate is depressed, but which parallel lines stop short of intersecting with any continuous printed area on the cardboard.
